UNITED STATES PATENT OFFICE.

JOHANN G. SCHWEERS, OF NEW YORK, N. Y., AND JOHN D. SCHWEERS,
OF ELIZABETH, NEW JERSEY.

AIR-SHIP.

SPECIFICATION forming part of Letters Patent No. 792,933, dated June 20, 1905.

Application filed October 10, 1903. Serial No. 176,572.

To all whom it may concern:

Be it known that we, JOHANN G. SCHWEERS, a citizen of the Empire of Germany, residing in New York, borough of the Bronx, and State 5 of New York, and JOHN D. SCHWEERS, a citizen of the United States, residing in Elizabeth, in the county of Union and State of New Jersey, have invented certain new and useful Improvements in Air-Ships, of which the following is a specification.

This invention relates to certain improvements in air-ships by which they can be propelled and steered in a very reliable and effective manner, in connection with an elongated counterbalancing-balloon of semicircular cross-section; and for this purpose the invention consists of an air-ship in which the weight of the supporting-frame is counterbalanced by a balloon and in which the propelling mechanism is composed of a number of sets of wings which are made to rotate on their axes, said wings being supported by shafts rotatable in the ends of radial arms forming frames that are also rotatable, the frames on 15 one side of the balloon being rotated in opposite direction to the frames at the opposite side of the same, the rotary motion being imparted to the frames and wings by suitable motion-transmitting devices operated by suitable motors.

The invention consists, further, of means for adjusting the entire system of wings on the supporting-frame so as to vary the angle of the wings when impinging against the air.

In the accompanying drawings, Figure 1 is a perspective view of our improved air-ship, showing the propelling-wings and steering device. Fig. 2 is a rear elevation of the same. Fig. 3 is a plan view of the rear part of the air-ship. Fig. 4 is a plan view of one of the rotating propelling-wings with its rotary frame. Fig. 5 is a side elevation of Fig. 4 with parts of the rotary frame broken away, showing the mechanism for shifting the wings on their 20 axes, so as to place them at a certain angle to the direction of motion. Fig. 6 is a similar side elevation showing the wing shifted askew on its axis. Fig. 7 is a detail section of the shifting mechanism employed, taken on line

77, Fig. 5; and Fig. 8 is an enlarged side elevation showing the mechanism for shifting the wings and for feathering the same.

Similar letters of reference indicate corresponding parts.

Referring to the drawings, A represents the main frame of our improved air-ship, which frame is formed of a bottom platform a , a top platform a' , and upright standards a^2 and inclined braces a^3 , by which the extensions of the frame of the top platform are braced. The main frame is preferably made of seamless steel or aluminium tubes of suitable strength and lightness, that are connected at their corners by suitable connecting-pieces. The lower platform a serves for supporting different motors by which the propelling devices are operated, and which motors may be of any approved construction combining power with the greatest possible lightness.

On the top platform a' is supported an elongated balloon B of any suitable construction, which is flattened at the lower part, so as to rest on the top platform, and of approximately semicircular cross-section at its upper part and tapered off at the ends. The balloon B is made of sufficient size so as to counterbalance the weight of the main frame, the motors, and the propelling devices, so that a sufficient balance is imparted to the air-ship, whereby the same is completely brought within the control of the propelling and steering devices.

The propelling devices are supported at the jointure of the inclined braces a^3 and the lateral extensions a^4 of the upper platform a' . These devices are composed of radiating arms F, forming frames which are rotatable on the shafts F', being supported in journal-bearings f. Each of said propelling-frames has secured to it a sprocket-wheel m, which is connected by a chain q with either one of two oppositely-rotating driving-shafts S or S', according to the position occupied by the propelling-frame at the left or right, respectively, of the main frame, said driving-shafts being supported in bearings in the bottom platform a . These shafts receive their rotary motion from suitable motors, (not shown,) also supported by bottom frame a , there being pref-

erably one motor for each set of propelling-frames. In the embodiment illustrated three sets of propelling-frames are shown at each side of the balloon; but it is obvious that any 5 number of such frames may be used, according to the length of the same and the size of the air-ship. The radiating arms F, which form the propelling-frames, are provided at their outer ends with journal-bearings n, in which 10 the shafts K of the propelling-wings C rotate. The wings C consist of oblong or rectangular frames C', over which silk, canvas, or other similar fabric is stretched. Secured to the central portion is a sprocket-wheel p. Alined 15 with these sprockets p are a number of stationary sprockets p², of approximately half the diameter of the sprockets p, said sprockets p² being secured to angularly-shiftable sleeves G, carried by the shafts F'. Transmission- 20 chains p' connect the sprockets p of the wings with said stationary sprockets p² and serve to effect the proper feathering of said wings, as will now be described. The feathering of the wings C is effected as follows: The sprocket- 25 wheels p² are rigidly attached to the shaft F' in a manner to be hereinafter described and the sprockets p are rigidly secured to the wings C. Consequently when the arms F are rotated about said stationary sprockets p² the 30 motion imparted to the sprocket-wheels p by means of the chains is similar to that which would be produced by rotating the central shaft F' and holding the arms F rigid—that is, the sprocket-wheels p and the wings are 35 rotated with respect to arms F. The sprocket-wheels p² are half the size of the sprocket-wheels p, so that in one revolution of the arms the wings will turn a half-revolution with respect to the same, and consequently by adjust- 40 ing the wings with respect to the stationary shaft the proper feathering of the wings will be brought about. The relative rotation of the shafts R and the frames F is such that on the downward movement of the arms of the 45 latter the wings arrange themselves horizontally, and so present their full surface to the air immediately beneath the same. The reaction caused thereby is sufficient to raise the balloon upwardly. When the wings arrive in 50 their lowermost position, they are rotated around their axis R, so that on their upward movement they are arranged vertically, and so present no retarding-surfaces to the air on their upward movement, so as to offer the least resistance to the air. The wing next following in the meantime descends and again 55 imparts an upward movement to the ship. The frames, with their independently-rotating wings, impart the upward propelling motion 60 to the structure, while the steering and partial forward motion is imparted to the air-ship by a propeller P³, which is arranged at the rear end of the upper platform, the shaft K of said propeller being supported in bear- 65 ings of a horizontal auxiliary platform a⁶, that

is provided with a slotted guide-rail for the movable journal-bearings a⁷ of the propeller-shaft, the inner end of the propeller-shaft being connected by a universal joint a⁸ with a horizontal shaft S³, supported in bearings 70 below the top platform. To this shaft rotary motion is imparted from one of the motors by suitable motion-transmitting gear. The movable journal-bearing a⁷ of the propeller-shaft is moved over the semicircular platform a⁶ in 75 one or the other direction, according to the direction of motion which is imparted to the air-ship. Suitable guide-ropes a¹⁰ are connected with the propeller-shaft and pass over pulleys a⁹ to the governing-board (not shown) 80 of the motorman. The sprockets p² on the shafts F' of the frames F are adjustable on the shafts F', by means of which the angle with which the wings impinge against the air is changed. Hereby the speed of air-ship is 85 governed.

For the purpose of improving and accelerating not alone the forward action, but also the steering action, a special mechanism is provided by which the position of the individual wings may be shifted askew, as shown in the position shown in Fig. 6. For this purpose a special lever-operated shifting device is used, which is shown in Figs. 5 and 7 and consists of a sleeve G, that is placed on 90 the shaft F' of the triangular rotary frames F, said sleeve G being provided with set-screws g³ and transverse slots g, that are guided on headed studs g' of said shaft, so as to permit a certain degree of angular motion 95 to the shifting sleeve G, on which the sprocket-wheels p² are fastened. To the front end of the shifting sleeve G in front of the main sprocket-wheel, by which rotary motion is imparted to the frames, are arranged diametrical arms g⁴, 100 which are connected by pivot-rods g⁵ with equidistant points on a fulcrumed lever L, which is arranged on a shaft g⁶, supported by the main frame, which extends the full length 105 of the balloon and which is connected to the different sets of wings. This shaft acts as a fulcrum of the lever, as shown in Fig. 4, so that all the wings at one side of the balloon B can be shifted simultaneously. By moving 110 the lever in the direction shown by the arrow 115 in Fig. 5 the sleeve G is shifted, and thereby the motion-transmitting sprocket-wheels, by which rotary motion is transmitted to the wings, are shifted simultaneously therewith. The shifting motion is imparted to one end of the wings only, while the opposite 120 end remains stationary, so that one side of the wings is set slightly askew of the other side, while their rotation on their axes is not impaired thereby. In order to allow the wings 125 to be shifted in this manner, a certain amount of play is necessary between the sprocket-wheel p and the shaft R at the side opposite to the shifting mechanism, and, in fact, there must also be a certain amount in the connec- 130

tions at the corners of the wings. By this means the wings may be shifted to a very noticeable degree. By the shifting of the wings out of their former position the air-ship is forced forwardly or backwardly, depending on the direction of the wings. If but one set of wings be set askew, a steering motion to one side or the other, according as one set of wings is shifted in relation to the set of wings on the opposite side by the shifting mechanism, can be attained. The shifting mechanism may be arranged at an intermediate point of the supporting-frame and in immediate proximity to the motorman, so that he can readily grasp the lever for setting the wings into proper inclined position, so as to produce the additional steering effect, which is auxiliary to the steering action of the propeller, or shift the wings askew, so as to cause either a forward or backward motion.

By the combined action of the steering-propeller and the adjustment of the wings to proper angle a very efficient steering action is obtained, while the shifting of one side of the wings in one or the opposite direction, so as to be askew with the other side, controls the forward and backward motion of the air-ship.

We claim as new and desire to secure by Letters Patent—

1. In an air-ship, the combination with a main frame and a balloon attached thereto, of main shafts on said frame, rotatable propelling-frames on said main shafts, each frame having a plurality of radial arms, wing-shafts supported at the outer ends of said arms, wings flexibly mounted on said wing-shafts, means for rotating said propelling-frames, and means for varying the position of one side of each wing with respect to the other side of the same.

2. In an air-ship, the combination, with a main frame and a balloon attached thereto, of main shafts mounted on said main frame, propelling-frames rotatable on said main shafts, each frame comprising a plurality of radial

arms, wing-shafts supported at the outer ends of said arms, wings flexibly mounted on said wing-shafts, means for rotating said propelling-frames, and means for angularly shifting either side of each wing independently of the other side thereof.

3. In an air-ship, the combination, with a main frame and a balloon attached thereto, of stationary main shafts mounted at either side of said main frame, propelling-frames rotatable on said main shafts, means for rotating said propelling-frames, wing-shafts rotatable in said propelling-frames, wings flexibly mounted on said wing-shafts and provided at either end with a fixed sprocket, sprockets carried by said main shafts, and sprocket-chains connecting the sprockets on the main shafts with the sprockets of the wings, the sprockets on the former being angularly shiftable so as to permit the independent angular shifting of either side of each wing.

4. In an air-ship, the combination, with a balloon and a frame carried thereby, of stationary main shafts mounted on said frame, propelling-frames rotatable on said main shafts, wing-shafts rotatable on said frames, wings flexibly mounted on said wing-shafts and provided at either side with a fixed sprocket, means for rotating said propelling-frames, angularly shiftable sleeves on said main shafts, sprockets carried by said sleeves, sprocket-chains connecting said first and last named sprockets, whereby the rotation of said propelling-frames effects the feathering of said wings, and means for adjusting said sleeves so as to vary the position of one side of each wing with respect to the other side thereof.

In testimony that we claim the foregoing as our invention we have signed our names in presence of two subscribing witnesses.
